C. J. WILLIAMS

ADJUSTABLE STRIKER PLATE

Filed Dec. 15. 1924

Inventor
Clifford J. Williams

38, W. Whittemore, Hubbard Whittemore
+ Bellamy, attorneys.

UNITED STATES PATENT OFFICE.

CLIFFORD J. WILLIAMS, OF DETROIT, MICHIGAN, ASSIGNOR TO BRIGGS MANUFACTURING COMPANY, OF DETROIT, MICHIGAN, A CORPORATION OF MICHIGAN.

ADJUSTABLE STRIKER PLATE.

Application filed December 15, 1924. Serial No. 756,141.

This invention relates generally to striker plates and refers more particularly to those designed for use in connection with the movable bolts of vehicle door locks and latches.

5 One of the essential objects of the invention is to provide a plurality of striker plates that are preferably arranged in tandem and are adapted to be alternately engaged by the bolt of the lock for holding 60 the door in either partially closed position or in fully closed position with respect to a suitable door jamb.

Another object is to provide a striker 65 plate of this type that may be readily adjusted transversely of the jamb without interfering with the usual trimming material of the vehicle body for taking up wear and preventing rattling.

10 A further object is to provide a construction in which the adjustment of the striker plate transversely of the jamb is preferably controlled by means that is adjustable longitudinally of the jamb.

Still another object is to provide strong 15 and durable striker plates that are simple in construction and can be manufactured at a comparatively low cost.

With the above and other objects in view the invention consists in certain novel features of construction, combinations and arrangements of parts as will be more fully described and particularly pointed out in the appended claims.

In the accompanying drawing:

20 Figure 1 is a fragmentary side elevation of a door jamb with the striker plates embodying my invention attached thereto.

Figure 2 is a cross sectional view taken on the line 2—2 of Figure 1.

25 Figure 3 is a fragmentary perspective view of one of the sections of the door jamb with the adjustable striker plate mounted thereon.

Figure 4 is a detail view of the retainer 30 plate.

Figure 5 is a detail view of the oblong plate.

Figure 6 is a detail view of the adjustable 35 striker plate.

40 Referring now to the drawing in which like characters of reference designate corresponding parts throughout the several views, the numeral 1 designates a door jamb preferably of a vehicle body. This jamb may be formed of any suitable material

and may be any shape desired, however it is preferably formed of two sheet metal stampings 2 and 3 respectively. As shown, the stamping 2 is preferably channel-shape in cross section and is provided at its forward edge with a laterally extending flange 4, while the stamping 3 is also preferably channel-shape in cross section and has one flange 5 thereof overlapping the lateral flange 4 of the stamping 2. These overlapping flanges may be secured together by any suitable means but are preferably welded together.

50 In order that a swinging door 6 may be held partially closed or fully closed with respect to the jamb 1, I preferably provide two striker plates 7 and 8 respectively that are preferably arranged in tandem upon the door jamb 1 and are adapted to be engaged by the movable bolt 9 of a lock carried by the door 6.

55 The striker plate 7 is preferably formed of sheet metal and is preferably permanently secured to the jamb section 3, while the striker plate 8 is also preferably formed of sheet metal and is adjustable transversely of the section 2 for taking up wear and preventing the bolt 9 from rattling. As shown, the striker plate 7 is preferably wedge-shape in form and is provided at its opposite sides 60 with the laterally extending attaching ears 10 which are preferably riveted to the flange 5 of the jamb section 3. The striker plate 8 is also preferably wedge-shape in form and is movable longitudinally of an elongated opening 11 that extends transversely of the jamb section 2 from the inner edge of the lateral flange 4 to a point adjacent to the rear flange 12. For supporting the plate 8 in the opening 11, I have provided a 65 retainer plate 13 that preferably bridges the opening 11 and is permanently secured to the section 2. As shown, this retainer plate 13 is preferably riveted at its forward end to the lateral flange 4 of the section 2 and is provided at its rear end with a lateral flange 14 that is secured to the rear flange 12 of the section 2.

70 In order that the inner striker plate 8 may be readily adjusted transversely of the jamb 1 without interfering with the usual trimming material (not shown) of the vehicle body, the retainer plate 13 is preferably provided with a relatively narrow transversely extending slot 15 and a rela- 75

tively wide longitudinally extending slot 16. As shown, the transversely extending slot 15 is adapted to receive the shank of a suitable headed element such as a screw 17 which extends through a circular opening 18 in the central depressed portion 19 of the inclined wall 20 of the striker plate 8, while the longitudinally extending slot 16 connects into the slot 15 and is adapted to receive a flat lug or extension 21 projecting from the rear wall 22 of the striker plate 8.

In order that the adjustment of the striker plate 8 transversely of the jamb 1 may be controlled by means movable longitudinally of the jamb, I preferably provide an oblong plate 23 that is preferably slidably mounted in spaced guide loops 24 struck out from the retainer plate 13 and is preferably provided with a longitudinally extending slot 25 having a series of steps 26 at its forward side edge that are adapted to be alternately engaged by the lug 21 for adjusting the striker plate 8 transversely of the jamb. Thus, the oblong plate 23 may be adjusted upwardly in the guides 24 when it is desired to adjust the striker plate 8 rearwardly, and may be adjusted downwardly in the guides 24 when it is desired to adjust the striker plate 8 forwardly. In this connection, it will be noted that the plate 23 is preferably provided at its upper end with a suitable lug or projection 27 that is engageable with the upper edge of the retainer plate 13 for limiting the downward sliding movement of the oblong plate.

For retaining the striker plate 8 in adjusted position, the oblong plate 23 is preferably provided with a series of threaded openings 28 that are preferably arranged in a line extending longitudinally of the plate 23 so that they may alternately register with the transversely extending slot 15 in the retainer plate 13, when the oblong plate 23 is adjusted longitudinally of the jamb 1. These openings 28 are also spaced a predetermined distance apart and are arranged in such a way with respect to the steps 26 that when one of the openings 28 registers with the transversely extending slot 15 in the retainer plate, the distance between one end wall 29 of one of the steps and the upper end wall 30 of the slot 16 is substantially equal to the width of the lug 21. Thus, when the screw 17 is moved through the opening 18 in the inclined wall 20 of the striker plate 8 and the transversely extending slot 15 in the retainer plate 13 and is engaged with one of the openings 28, the oblong plate 23 and striker plate 8 will be held in adjusted position.

In use, the oblong plate 23 is adjusted when the striker plate 8 is removed to position the proper opening 28 in registration with the slot 15, whereupon the striker plate 8 is applied to the retainer plate 13 so that

the lug 21 engages the proper step 26, and the opening 18 in the inclined wall 20 of the striker plate 8 registers with the transversely extending slot 15. The screw 17 is then moved through the opening 18 and slot 15 and is engaged with the registering threaded opening 28. Thus, the striker plate 8 may be readily adjusted without interfering with the usual trimming material (not shown) of the vehicle body for taking up wear and preventing the bolt 9 from rattling.

Inasmuch as the striker plates 7 and 8 are formed of sheet metal, it is readily apparent that the cost of manufacturing such devices has been reduced to a minimum. Moreover, the arrangement is such that the parts may be easily and quickly assembled or taken apart whenever desired.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim as my invention is:

1. A device of the class described including a supporting member, a striker plate adjustable transversely thereof, a lug projecting from said striker plate, and means movable longitudinally of said supporting member and engageable with said lug for controlling the adjustment of said striker plate transversely of said supporting member.

2. A device of the class described including a retainer plate, a striker plate adjustable transversely thereof, a lug projecting from said striker plate, and a plate movable longitudinally of said retainer plate having a stepped portion engageable with said lug for controlling the adjustment of said striker plate transversely of said retainer plate.

3. A device of the class described including a retainer plate, a striker plate adjustable transversely thereof, means controlling the transverse adjustment of said striker plate including a member movable longitudinally of said retainer plate, and means engaging said retainer plate and member for holding said striker plate in adjusted position.

4. A device of the class described, a retainer plate, a striker plate adjustable transversely thereof, means controlling the transverse adjustment of the striker plate including a plate movable longitudinally of said retainer plate, guide means for said last mentioned plate carried by said retainer plate, and an element engaging said retainer plate and last mentioned plate for holding said striker plate in adjusted position.

5. A device of the class described including a retainer plate having a transversely extending slot, a striker plate slidable upon said retainer plate, means for controlling the sliding movement of said striker plate including a part movable longitudinally of said retainer plate, and an element extending through the slot in said retainer plate engageable with said member for retaining the striker plate in adjusted position.

6. A device of the class described including a retainer plate having a longitudinally extending slot, a striker plate slidable upon the retainer plate and having an extension movable in said longitudinally extending slot, and means for controlling the adjustment of said striker plate including a member movable longitudinally of the retainer plate having a stepped portion engageable with said extension.

7. A device of the class described comprising a retainer plate having a longitudinally extending slot and a transversely extending slot, a striker plate slidably mounted upon the retainer plate having a lug movable in said longitudinally extending slot, means for controlling the adjustment of said striker plate including a member movable transversely of the retainer plate and having a stepped portion engageable with said lug, and means for holding said striker plate in adjusted position including a member extending through the transversely extending slot in the retainer plate and engageable with the member aforesaid.

8. A device of the class described comprising a retainer plate having a longitudinally extending slot and a transversely extending slot, a striker plate slidably mounted on the retainer plate having the lug movable in the longitudinally extending slot, means for controlling the sliding movement of the striker plate including a plate movable longitudinally of the retainer plate and having a stepped portion engageable with said lug, said last mentioned plate also having a series of openings therein, and means for retaining said striker plate in adjusted position including an element extending through the transversely extending slot in said retainer plate and engageable with one of the openings in said last mentioned plate.

9. A device of the class described comprising a retainer plate, an adjustable striker plate having an extension, a plate slidably mounted on said retainer plate having means adapted to be engaged by the extension of the striker plate for regulating

the adjustment of the latter in one direction, and means extending transversely of said retainer and last mentioned plates for holding said striker plate in adjusted position.

10. A device of the class described comprising a retainer plate having a longitudinally extending slot and a transversely extending slot therein, a plate slidably mounted on said retainer plate having a series of stepped shoulders along one longitudinal edge thereof and a series of longitudinally spaced openings alternately registerable with the transversely extending slot in said retainer plate, a striker plate having an extension movable in the longitudinally extending slot in said retainer plate and alternately engageable with said shoulders, said openings being arranged in such a way with respect to said shoulders that the distance between one of the shoulders and the opposed end wall of said longitudinally extending slots aforesaid is substantially equal to one dimension of the striker extension when one of said openings aforesaid registers with the transversely extending slot in the retainer plate, and means for retaining said striker plate in adjusted position, said means including an element movable in the transversely extending slot aforesaid.

11. A device of the class described comprising a retainer plate having an opening therein, an adjustable member having an opening registering with the opening in said retainer plate and having a plurality of stepped shoulders, a striker plate adjustable upon said retainer plate and having a lug extending through said registering openings and engaging one of said shoulders, and means for holding said striker plate in adjusted position including means detachably maintaining said lug in engagement with said shoulder.

12. A device of the class described comprising a retainer plate having an opening therein, an adjustable member having a plurality of spaced openings therein and having a plurality of stepped shoulders, a striker plate adjustable upon said retainer plate and having a lug extending through the opening in said retainer plate and engaging one of said shoulders, and means for maintaining said lug in engagement with said shoulder including an element engaging said striker plate, retainer plate, and one of the openings in said member.

In testimony whereof I affix my signature.

CLIFFORD J. WILLIAMS.
